JUG

Richard L. Platte, Ann Arbor, Mich., assignor to Hoover
Ball and Bearing Company, Saline, Mich.

Filed Sept. 16, 1963, Ser. No. 76,599

Term of patent 14 years

(Cl. D58—5)

FIGURE 1 is a side elevational view of a jug, showing my new design;

FIGURE 2 is a rear elevational view thereof;

FIGURE 3 is a front elevational view thereof;

FIGURE 4 is a top plan view thereof; and

FIGURE 5 is a sectional view taken on line 5—5 of FIGURE 1.

The dominant features of my design reside in the portions shown in full lines.

I claim:

The ornamental design of a jug, as shown and described.
